UNITED STATES PATENT OFFICE

108,314

DESIGN FOR AN ADVERTISING TOWER

Walter G. Baryl, Evanston, Ill., assignor to Loop
Auto Parks, Chicago, Ill., a corporation of Illi-
nois

Application March 1, 1937, Serial No. 67,932

Term of patent 3½ years

To all whom it may concern:

Be it known that I, Walter G. Baryl, a citizen of the United States, residing at Evanston, in the county of Cook and State of Illinois, have invented a new, original, and ornamental Design for an Advertising Tower, of which the following is a specification, reference being had to the accompanying drawing, forming part thereof.

In the drawing:

Fig. 1 is a perspective view of an advertising tower embodying my design; and

Fig. 2 is a transverse sectional view on the line 2—2 of Fig. 1 looking in the direction of the arrows.

The characteristic features of the tower reside in the relatively large upright base having opposed converging walls merging into a conical upper portion and terminating in a shank having a relatively large sphere at its upper end and a rod extending downwardly of the shank and outwardly of the base, the rod supporting at its outer end a relatively small figure of an airplane laterally of the base and substantially in the plane of the upper conical portion of the base.

I claim:

The ornamental design for an advertising tower, as shown and described.

WALTER G. BARYL.
